LUGGAGE BAG

Leonard George Arpin, Fort Lauderdale, Fla., assignor of one-half to Howard C. Jelks, Fort Lauderdale, Fla.

Application October 11, 1933, Serial No. 693,075

11 Claims. (Cl. 190—43)

This invention relates to a luggage bag primarily adapted for vehicle travel, and constitutes an improvement of the luggage bag disclosed in my co-pending application, Ser. No. 671,977, filed May 20, 1933.

The improvements consist mainly in forming the luggage bag so that it can be folded and in providing the ends with handles so that it can be readily carried as a suit case in its folded relation. Other features of improvement will be pointed out as the description proceeds.

The invention comprises the novel structure and combination of parts hereinafter described, and more particularly pointed out and defined in the appended claims.

In the accompanying drawings which illustrate a preferred form of this invention, and in which similar reference numerals refer to similar features in the different views:

Figure 1 is a side elevational view of the luggage bag with a part broken away to illustrate the interior thereof.

Figure 2 is a sectional view taken upon the line II—II of Figure 1.

Figure 3 is an end elevational view of the bag in folded relation.

Figure 4 is a bottom plan view of the bag in its folded relation.

Figure 5 is an enlarged fragmentary sectional view thru the bottom of the bag.

Figure 6 is an enlarged and fragmentary sectional view of one end of the bag.

Figure 7 is an enlarged and fragmentary sectional view taken at the other end of the bag.

Figure 8 is a fragmentary elevational view with parts shown in section, illustrating a feature of construction.

The illustrated embodiment of this invention shows a flexible bag consisting of sides 1 and 2 which may be formed of leather or any suitable material. A web 3 of similar material connects the two sides to form the bag. The edges of the sides are preferably secured to the web by bending the edge portions of the web outwardly to form seats for the sides, folding a strip of leather or the like over the edge portions as shown in Figures 6 and 7, and sewing the parts together. The web is slit to provide an entrance to the bag and this slit is closed by a zipper 5.

The ends of the bag are reinforced and provided with handles 6 so that the bag may be readily carried when folded as shown in Figure 3. The reinforcement at the lower end of the bag is shown in Figure 6 and consists of a fibre board 7 positioned against the web 3, with a lining mem-

ber 8 secured thereon. This lining member 8 has its ends turned outwardly so that the same may be sewed between the sides and the web. The reinforcement at the upper end of the bag is shown in Figures 7 and 8 and consists of a metal plate 9 which may be riveted or secured to the web in any suitable manner. The ends of the plate 9 are bent downwardly as indicated at 9a (Figures 1 and 8) to form upper corners for the bag for supporting the web. A stirrup 10 may be secured to the plate 9 for supporting clothes hangers 11.

The medial portion of the side 2 of the bag is also reinforced to serve as a bottom for the bag when the same is folded as shown in Figure 3. This reinforcement is best shown in Figure 5 and consists of a fibre board 12 positioned adjacent the medial portion of the side and secured in place by a flexible covering member 13 secured at its margins to the side 2. Brass knobs 14 or the like are attached to the bag over the reinforcement 12 as shown in Figure 5 to support the bag in its folded relation.

A plurality of pockets may be formed upon the side 2 of the bag. A fabric 15 may be secured across the upper portion of the bag in any suitable manner to form a pocket for holding articles. This pocket may be divided into two pockets by a line of stitching 16 (Figure 1) if desired.

A second fabric piece 17 may be secured at its edges and its bottom to the side 2 to form a second pocket. This fabric may be buttoned at its upper end to the fabric 15 by means of the button 18.

A lower pocket is provided for holding shoes or the like. This pocket is formed by securing a flap of fabric 19 adjacent the side 1 at the bottom of the bag and extending the same across the bag and securing the same to the side 2 by buttons 20 or the like as shown in Figures 1 and 2. It will be noted that this pocket has a width equal to the width of the bag and that the bottom thereof is formed by the bottom of the bag.

When the bag is folded as shown in Figure 3, it is desirable to maintain the same in such folded relation when set down upon the floor or ground. For this purpose, a piece of leather 21 may be secured to one handle 6 for embracing the other handle 6 when the same is brought into contact therewith. The ends of the strip 21 may be secured together by a snap fastener 22. This strap will tie the two handles together and prevent the bag from spreading when the same is folded.

It will be appreciated that this bag will sustain clothes in suspended relation when the same is

in the position shown in Figure 1. The ends of the bag may, however, be brought together by folding the bag as shown in Figure 1. In such position, the handles may be secured together so that the bag may be converted into a grip and handled in the manner of a grip. This feature renders the bag extremely convenient for use in vehicle travel or other purposes. The clothes are not apt to get wrinkled as they are only folded in one place.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a luggage bag, flexible side members, a web connecting said side members, reinforcements at the ends of said bag, a handle secured to each reinforcement whereby the bag may be folded to bring said handles into contacting relation and a reinforcement upon one side of the bag for forming a bottom therefor in its folded relation.

2. In a luggage bag, a pair of flexible side members, a web connecting said members, means for reinforcing opposite portions of said web and a handle secured to each reinforced portion whereby said bag may be folded and carried by said handles.

3. In a luggage bag, flexible side members, a web connecting said members, a handle at each end of said bag, a reinforcement upon the interior medial portion of one of said members adapted for forming the bottom of said bag when the same is folded to bring said handles together.

4. In a luggage bag, flexible side members, a flexible web connecting said members, said web having an entrance slot for access to the bag, reinforcements upon opposite portions of said web and a handle attached to each reinforcement.

5. In a luggage bag, flexible side members, a web connecting said members, said web having an entrance slot, a handle at each end of said bag and a reinforcement upon the interior medial portion of one side of the bag for forming the bottom therefor when said bag is folded to bring said handles adjacent each other.

6. A luggage bag comprising flexible side members, a flexible web having outwardly directed

flanges secured to the edges of said side members, said web having reinforcements upon opposite portions, handles secured to said reinforcements whereby said bag may be folded at midsection and a reinforcement at such midsection of the bag for supporting the same in its folded relation.

7. In a luggage bag, flexible side members, a flexible web having outwardly directed flanges connected to the edges of said side members, reinforcements upon spaced portions of said web and forming the top and bottom portions of said bag, a handle attached to each reinforcement, a reinforcement upon the medial portion of one side of the bag for forming a secondary bottom for the bag when the same is folded for bringing said handles together.

8. In a luggage bag, flexible side members, a flexible web connecting said side members, spaced reinforcements upon said web forming the top and bottom of said bag, a handle secured to each reinforcement, a reinforcement upon the medial portion of one side of the bag for forming a secondary bottom for the bag when the same is folded to bring said handles together.

9. A luggage bag comprising flexible side members and an intermediate web forming the top, bottom and side edges of the bag, a reinforcement at the top of the bag, a reinforcement at the bottom of the bag, a handle attached to each reinforcement, and a reinforcement upon the medial portion of one side member adapted for forming a secondary bottom when the portions upon each side thereof are folded in the same direction for bringing said handles together.

10. A luggage bag comprising flexible side members and an intermediate web and folded to provide a horizontal portion through which clothes are adapted to extend and substantially vertical portions at an angle to said horizontal portions through which clothes are adapted to extend, means for reinforcing said horizontal portion, and a handle at the upper end of each vertical portion.

11. A luggage bag comprising continuous side members and an intermediate web and folded to provide a U-shaped device, means for reinforcing the bottom of the U-shaped device to provide a secondary bottom, and a handle upon each end of the bag for carrying the same in its folded relation.

LEONARD GEORGE ARPIN.
